UNITED STATES PATENT OFFICE.

HERBERT L. BROWN, OF PETERSBURG, VIRGINIA.

BOTTLE-CAPPING MACHINE.

1,379,161.

Specification of Letters Patent. Patented May 24, 1921.

Application filed September 17, 1920. Serial No. 410,829.

To all whom it may concern:

Be it known that I, HERBERT L. BROWN, a citizen of the United States of America, and a resident of Petersburg, county of Dinwiddie, die, and State of Virginia, have invented certain new and useful Improvements in Bottle-Capping Machines, of which the following is a full and clear specification.

The object of this invention is to provide an inexpensive, simple and practical hand-operated device for capping bottles, as more fully hereinafter set forth.

In the drawing—

Figure 1 is a perspective view and Fig. 2 is a vertical longitudinal sectional view of my improved apparatus.

In the drawing, *a* designates a base-plate which is adapted to be fastened to a table or other support. Anchored in this base-plate is a pair of vertical parallel rods *b*, and connecting the upper free ends of these rods is a cross-head *c* which is slidably mounted on the rods, being provided with a pair of eyes *d* which fit the rods. The inner face of each rod is provided with a series of notches *e*, and the cross-head carries on its upper side a pivoted flat bar *f* whose ends are adapted to enter the notches in the respective rods to thus lock the cross-head in its adjusted position, the series of notches being long enough to accommodate bottles of ordinary height. In the under side of the cross-head is a central recess *g* for receiving the cap and crimping it on the mouth of the bottle when the bottle is pushed upwardly against the cross-head.

The bottle-rest consists of a disk *h* provided with pairs of lugs *i* at diametrically opposite points for embracing the rods *b*, to thus guide the bottle-rest in the up-and-down movements. The disk *h* is provided with an annular upstanding flange *j* to hold the bottle in place, and at the back the flange is provided with an upstanding lug *k*, against which the bottom of the bottle strikes

when the bottle is placed in position on the rest to thereby center the bottle on the rest.

Depending from the disk *h* is a hub *l*, and centrally through this hub extends a rod *m* which is affixed rigidly to the base *a*, to thereby serve as an additional guide for the bottle-rest. This depending hub or tube *l* is provided with a pair of wings *n* extending in opposite directions from the hub, the lower ends of these wings being rounded at *o* to receive the forked arms *p* of a lever *q* carrying a pin *r* which is pivotally mounted on a lug *s* rising from the base at a point a short distance in front of the center of the base. The pin, as stated, is carried by the lever, and is journaled in the lug *s*, so that by depressing the outer end of the lever the bottle-rest will be elevated.

The nature and scope of the invention having been thus indicated and its preferred embodiment having been specifically described, what is claimed as new is:

1. In a bottle-capping machine, a base, a pair of parallel rods rising therefrom, means on the base for raising the bottle, and abutment means carried at the upper ends of the rods embodying a cross-bar slidably mounted on the rods and having a crimping recess centrally on its top side a locking bar, said 70 parallel rods being each provided with a series of notches in its inner face adapted to receive the ends of said pivoted bar.

2. In a bottle-capping machine, a base, up-standing rods on the base, a cross-head carried at the upper ends of the rods, a bottle-support slidably engaging the rods and provided with a pair of depending wings on its under side, a central guide-post for said bottle-rest, and a lever pivotally mounted on the base and having a forked inner end engaging under the lower edges of said wings.

In testimony whereof I hereunto affix my signature.

HERBERT L. BROWN.
